UNITED STATES PATENT OFFICE.

HENRY W. ROUNTREE, OF RICHMOND, VIRGINIA, ASSIGNOR TO H. W. ROUNTREE & BROTHER TRUNK & BAG COMPANY, INCORPORATED, OF RICHMOND, VIRGINIA.

COMBINED FOLLOWER AND IRONING BOARD.

Application filed March 6, 1922. Serial No. 541,453.

To all whom it may concern:

Be it known that I, HENRY W. ROUNTREE, a citizen of the United States, residing at Richmond, in the county of Henrico and State of Virginia, have invented a new and useful Improvement in Combined Followers and Ironing Boards, of which the following is a specification.

This invention, which generally has reference to improvements in wardrobe trunks, is particularly directed to the provision of a follower board which is usually adjusted to act as a clothes presser and which operates within the compartment of the trunk 15 in which the clothes are hung on hanger members that are slidably suspended from over-head rods located along the inside upper edges of the opposite side portions of the trunk top, when the trunk is at the upright 20 opened position, and which can be quickly and conveniently removed from the rod supports and utilized as an ironing board, as desired.

Combined follower and ironing board devices for wardrobe trunks, heretofore provided and now in use, are of a somewhat complicated nature, relatively expensive to manufacture, especially for the cheaper grades of wardrobe trunks and whose cooperative 30 parts are so arranged that, more or less difficulty (particularly for ladies) is experienced, when adjusting the follower and holding it locked to the clothes pressing adjustments.

Followers or presser boards of the general type stated are in use in which the follower is provided with means for sustaining one end thereof on the trunk body and with the other or free end supported by upright devices or leg members for maintaining the follower in position for being conveniently used as an ironing board. The said type of combined follower and ironing board mentioned is open to the objections above noted, 40 since mechanical adjustment of the leg or vertical support for the board is necessary, to properly sustain the follower in its flat-wise or ironing board position.

Again, in the use of some of the known 50 combined clothes presser or followers and ironing board devices, the means utilized for adjusting the said combined devices, especially when used as a clothes presser, require considerable care in the handling 55 thereof, particularly when hanging ladies

dresses so that danger of tearing or otherwise injuring costly garments, is avoided.

My invention has for its object, first, to provide a clothes presser or follower that can be manufactured at such low cost that 60 its use is applicable for the cheapest grades of wardrobe trunks and its construction such that it can be advantageously used in connection with all grades and practically all styles of wardrobe trunks now on the 65 market.

Second, to provide a combined clothes follower or presser and ironing board for wardrobe trunks, so simple in its arrangement, that it can be more or less instantly 70 released from the garment pressing adjustment by anyone, without the need of any complicated manipulation of the parts and which can be readily and conveniently fitted onto the trunk body to serve as an ironing 75 board, as desired.

Third, to provide a device of the character and for the purposes stated, in which the danger of injury to garments of any kind, while fitting such device to the clothes pressing adjustment or removing it from the clothes hanging compartment of the trunk, to support it upon the trunk body to serve 80 as an ironing board, is positively overcome.

With other minor objects in view, that 85 will be hereinafter apparent, my invention comprehends the combined follower and ironing board for wardrobe trunks that embodies the peculiar features of construction and novel arrangement of parts, fully 90 explained in the following detailed description, especially stated in the appended claims and illustrated in the accompanying drawings, in which:

Figure 1 is a perspective view of a wardrobe trunk to which my invention is applied, the said invention being shown as a follower and in the clothes pressing position.

Figure 2 is a perspective view of my improved combined clothes presser or follower 100 and ironing appliance for wardrobe trunks.

Figure 3 is a perspective view of the wardrobe trunk, the follower device being illustrated as supported and in interengaged connection with the trunk drawers, 105 and in position for being conveniently utilized as an ironing board.

Figure 4 is a vertical section of a portion 110 of the clothes compartment of the wardrobe trunk, the follower device being shown in

the clothes pressing position and locked to such adjustment.

Figure 5 is a diagrammatic horizontal plan view of the follower board and the said view illustrates how the follower is sustained against lateral displacement or wobbling when supported by the trunk drawers, as in Figure 3.

Figure 6 is an illustrative diagram view 10 hereinafter specifically referred to.

In the drawings, is illustrated a modern type of wardrobe trunk that comprises two half sections so hinged together that, when opened, and the trunk is supported in up- 15 right position, as shown in Figure 1, the drawers that fill one compartment, and the clothes chest formed within the other compartment, have such relation that access to either of the said trunk compartments may 20 be conveniently and readily had.

In the trunk construction shown, the top of the clothes compartment has the usual trolley rods or hanger bars 2 secured to the inner upper portions of the opposite side 25 members 20, in the usual manner, and upon which the conventional type of clothes hanger devices 3 are supported and adapted for being slidably shifted when the clothes are moved together, and held under compres- 30 sion by the combined follower and ironing board, as is best shown in Figures 1 and 4, and the construction of which, together with the means for sustaining it in operative con- 35 nection with either the clothes compartment 1 or the drawers of the other compartment 5, constitutes the essential features of my invention.

In my construction, the combined follower and ironing board has the shape of the 40 ordinary ironing board and is of suitable length to provide a presser member that practically, when suspended as a clothes presser or follower, extends the full length of the garments hung in the clothes com- 45 partment, see Figures 1 and 4.

The combined presser and ironing board, designated 4, in practice, is covered with genuine press cloth and is well padded on 50 that side that engages the clothes and which constitutes the ironing surface 40, as shown.

To provide for a maximum rigidity of the upper end of the board and also for extending practically across the full width of the clothes compartment, the said upper end of 55 the board has lateral extensions 41—41 to the extreme ends of which are secured, in any suitable way, metal hanger hooks 6—6 which are so shaped that they may be quickly hung onto or lifted off the trolley or 60 hanger bars 2, as desired.

It will be readily apparent, by referring to Figures 1 to 4 of the drawings, if the board 4 is hung onto the opposite hanger rods or bars, the said board can be easily 65 pushed back to compress the hangers 3 with

their suspended clothing to a tightly closed up condition; as shown in Figure 4, and to hold the follower and the clothes to their compressed back position shown in the said Figure 4, suitable means, in the nature of locking elements, are cooperatively mounted upon the board and the opposite sides of the clothes compartment.

In the drawings, is illustrated a preferred arrangement of locking elements for holding the board to its clothes compressed adjustment and these are so arranged that they can be conveniently and almost instantly manipulated by any one, either when causing the board to follow back into the clothes compartment, or when it is desired to disconnect the follower board from the opposite side hangers or controls to apply more clothes hangers or when it is desired to use the board for ironing purposes.

Referring more particularly to Figure 2, which shows the combined follower and ironing board separate from the trunk, it will be seen that at a point about midway 90 its length, a strip 8, which is also in practice, fully covered with the usual press cloth, is rigidly secured, in any suitable way, across the bottom of the said board, and the said strip 8 is of a length equal that of the full width of the board 4 at its top edge, the reason for which will be presently explained.

The board 8 primarily acts as a stiffener for the ironing board 4 and, in connection with a cross cleat 9 that is also secured on the under side of the board 4, near its outer end, secures the board against bulging or splitting, a condition that frequently occurs during the constant use of the hot iron across the ironing surface.

The long strip 8 is a relatively wide one and by reason thereof it produces additional follower surface for pressing against the clothes and it also acts as a guard against possible entwining of soft fabrics around the oppositely shiftable locking rods 10 whose inner ends ride in a central keeper or housing 11 that is riveted to the cross strip 8. Each of the inner ends of the rods 10 has an outwardly projected compression finger 12 and each of the said fingers 12—12 are slidable in individual slots 13—13, formed in the said housing 11, as shown. The rods 10 extend in opposite direction along the strip 8 and have their ends guided in plates or keepers 14—14, it being understood that, in practice, the said rods 10 are normally distended by a coil spring 15 that is interposed between the inner adjacent ends of the said rods 10—10 and located 110 within the housing 11, as shown.

By providing the common type of spring distended locking rods, it follows that when pushing the board back to compress the hung clothes, the ends of the locking rods 130

10 may easily slip over and engage with horizontally disposed locking racks 16-16 attached to the opposite sides of the clothes compartment, as shown, it being also apparent 5 that to remove the follower device from the trunk body it is only necessary to squeeze the finger portions 12-12 of the rods 10-10 together to withdraw their rod ends from the racks 16-16 and thereby permit 10 lifting the said follower device off the hanger rods or members 3-3 at the upper edges of the opposite trunk sides, as before stated.

In addition to functioning as a means for stiffening the board 4 and to serve as guards 15 for holding the locking rods out of direct engagement with the clothes and as additional follower surfaces to engage the clothes the said cross strip 8 also functions 20 as a means for holding the board against a too free wobbling or lateral displacement of the device when it is utilized as an ironing board, as shown in Figure 3.

It will be noticed by referring to Figure 2 25 of the drawings, that my construction of combined follower and ironing board device can be conveniently supported, for use as an ironing board, by projecting the upper and widest end of the board, within a partly pulled out drawer 50 and under the bottom 30 of the closed drawer, located above the partly pulled out drawer 50. The top edge 51 of the pulled out drawer constitutes the support for the board 4 and the interengaging 35 of the large end of the board (that fits into the pulled out drawer) with the bottom of the closed drawer, constitutes a practically rigid support for the board as it is held in the horizontal position for being conveniently 40 used for ironing purposes, as shown.

It will be noticed, particularly by referring to Figure 5, that the large end of the board 4 is practically the full width of the drawer, the hook members 6-6 at the opposite 45 site sides tending to hold the board in its proper straight position, and to which position the board is further held by the cross strip 8 that engages the upper front edge of the pulled out drawer 50, such arrangement 50 of parts tending to avoid pulling the drawer 50, on which the board 4 rests, out further than necessary to provide the desired support for the board 4, and also against permitting a too free displacement or side wobbling 55 of the board 4, when using it in the manner shown in Figure 3.

Without the long cross strip 8, before mentioned, and which bears against the front upper edge of the open drawer 50, when the 60 appliance is used as an ironing board, the tendency of the said board, if used (without the strip 8) would, under very slight lateral pressure on the board, while ironing, cause such board to take the position, illustratively 65 indicated in the diagram, Figure 6, and

thereby cause the ironing board to become easily separated or disconnected from its bearings or supporting members.

From the foregoing description, taken in connection with the accompanying drawings, 70 the complete construction, the manner of its application and the advantages of my combined follower and ironing board appliance will be readily apparent to those familiar with the use or the manufacture of wardrobe 75 trunks.

My combined follower and ironing board has no mechanical devices that require careful adjusting to set the appliance either to the clothes pressing adjustment shown in 80 Figure 1, or in the ironing board position, shown in Figure 3. The construction of the appliance and the ease with which it can be hung in place in the clothes compartment or positioned between a pair of the trunk 85 drawers to hold it in place as an ironing board being such that a lady can readily place the combined follower and ironing board in such position as needed.

The appliance has such configuration that 90 no projecting parts are present that can be readily become entangled with the clothes against which the device is held, and its cost of manufacture is so low that it can be well used as an accessory to the cheaper grades 95 of wardrobe trunks as well as with the higher grade and expensive types of such trunks.

What I claim is:

1. As a new article, a combined follower 100 and ironing board device for wardrobe trunks provided with clothes hanger members at the upper edge of the clothes compartment and having a set of drawers in another compartment, the said device comprising a tapering board having lateral extensions at the upper end, a hook fitted to each of the said ends for fitting over the clothes hanger members to support the device as a follower, a cross strip attached to the board body whose ends extend practically the full width of the clothes compartment and the full width of the trunk drawers, the said strip constituting a follower portion when the device is adjusted as a clothes presser and operating as an abutment strip for engaging the outer top edge of a drawn out trunk drawer when the upper or wider end of the device is inserted into the partly drawn out drawer and projected under the next top drawer to bear against the bottom thereof when the device is sustained on the trunk drawers to serve as an ironing board. 115

2. A combined follower and ironing board 120 for wardrobe trunks composed of two hinged sections, one of which constitutes a clothes compartment and the other of which has a series of superimposed drawers, and trolley hangers at the opposite upper edges of the clothes compartment, the said combined fol- 130

lower and ironing board comprising a tapering board whose widest end has opposite lateral extensions each provided with a hanger hook, the said hooks constituting members for engaging the opposite sides of a drawer when the board is supported for use as an ironing board and adapted for engaging the trolley hangers in the clothes compartment when the board is used as a follower, the said combined follower and ironing board including a cross strip that constitutes an abutment for engaging the outer face of the drawer edge upon which the board rests when it is used as an ironing board and a support for finger released and

spring distended elements adapted for engaging and interlocking with the opposite side walls of the clothes compartment, when the board is used as a follower said board being adapted to be inserted into a partially opened drawer and lie with said hooks in engagement with the side walls of the drawer into which the board is projected, the top of the projected board engaging the under side of the next drawer above, whereby the board will be held against lateral movement and maintained substantially rigidly in place. 20 25

HENRY W. ROUNTREE.
